CAN MARKING MACHINE

George F. Jackson, Baltimore, Md., assignor to
Continental Can Company, Inc., New York,
N. Y., a corporation of New York

Application May 9, 1938, Serial No. 206,388

2 Claims. (Cl. 101—35)

The invention relates generally to identification stamping machines and primarily seeks to provide a novel machine for ink-stamping identifying characters upon the ends of cans being fed through the machine.

It is customary to apply to beverage containers, such as beer cans, suitable identifying markings, and these markings commonly take the form of numerals and are applied to the bottoms of the cans. In its more detailed nature, therefore, the invention seeks to provide a novel machine, continuously operating and connected with suitable delivery and discharge means for feeding cans to and from the machine, and embodying means for applying the markings to the cans while they are being continuously fed through the machine.

Another object of the invention is to provide a machine of the character stated embodying means for ink-stamping the can ends by a rolling contact.

Another object of the invention is to provide a novel ink-stamping roller, adjustable to accurately time the application of the marking, novel ink applying means, a novel turret structure rotatable in a vertical plane to continuously feed cans past the ink-stamping roller, and adjustable devices for enabling the handling of cans of different heights.

With the above and other objects in view that will hereinafter appear, the nature of the invention will be more fully understood by following the detailed description, the appended claims, and the several views illustrated in the accompanying drawings.

In the drawings:

Figure 1 is a left side elevation of my improved machine;

Fig. 2 is a part plan and part horizontal section, the plane of the sectional illustration being that which includes the axis of the ink-stamping devices;

Fig. 3 is a vertical cross section taken at the position of the ink-stamping devices;

Fig. 4 is a right side elevation, parts being broken away;

Fig. 5 is a detailed perspective view illustrating a fragment of a can and the ink-stamping rotor.

The machine includes a base 5 having mounting pads 6 for facilitating attachment of the machine upon the floor or any other suitable support. Right and left frame standards respectively designated 7 and 8 are removably secured as at 9 upon the base and are joined at their rear ends by a cross rod 10, at their front ends by a cross connecting angle 11, and at their upper

portions by cross rods 12 disposed in parallel spaced relation, as shown in Figures 2, 3 and 4 of the drawings.

Opposed feed-in casting members 13 are mounted as at 14 upon the cross rods 12 and serve to support feed-in trackage 15 to which cans to be marked are fed by gravity, as shown in Fig. 1 of the drawings.

In aligned bearings 17 and 18 provided respectively in the frame members 7 and 8, a cross shaft 10 19 is secured and serves as a support for a rotor sleeve 20 which is rotatable about said shaft.

A can feeding turret 21 is provided and is secured upon and rotatable with the sleeve 20, as shown in Figure 2 of the drawings. The turret 15 21 includes spaced flange portions peripherally notched as at 22 to provide eight can receiving pockets about the periphery of the turret. See Figs. 2, 3 and 4. A beveled gear driver ring 23 is secured to the right hand face of the turret, 20 as shown in Fig. 2.

The cans 16 fed into the machine on the trackage 15, as shown in Fig. 1 of the drawings, are deposited one by one into the receiving pockets of the turret, and as they are moved about in the clockwise direction, as shown in Fig. 1, they are peripherally retained by a track member 24 which is concentric with the turret and is secured at its upper end as at 25 to the rearmost cross rod 12, and as at 26 at its lower end to the cross rod 19. 25

The cans are received from the turret onto an offtake track 27, a suitable ejector plate 28 being disposed above the track 27 and extended into the turret between the flanges thereof, as indicated in dotted lines in Figs. 2 and 4 of the drawings. 35

For holding the cans against longitudinal displacement on the turret, I provide a stationary can gauging ring 29 which is secured as at 30 to the frame standard, as shown in Figs. 2 and 4 of the drawings. It will also be noted by reference to Fig. 2 of the drawings that the lower end of the sleeve 20 is externally threaded as at 31 to adjustably receive the abutment disc 32. The disc 32 40 45 cooperates with the ring 29 in preventing longitudinal displacement of the cans from the turret pockets, and, by adjustment of this disc toward and from the ring 29, the machine can be adapted for handling cans of different heights. The adjustments of the discs 32 can be secured by the jam nut 33. 50

The standard 7 includes a sleeve bearing portion 34 horizontally aligned with the axis of the transverse bearings 17, 18. A bearing 35, re- 55

movably secured as at 36 upon the standard 7, cooperates with the bearing portion 34 in rotatably supporting a driver shaft 37 on which is fixed a beveled pinion 38. The pinion 38 meshes with and imparts rotation to the driver ring 23 and the turret 21 to which it is secured. See Figs. 1 and 2 of the drawings. The shaft 37 is driven through suitable reduction gearing from a motor 39 supported upon the base 5.

10 A marking sleeve 40 is carried by the shaft 37 and is equipped with a grooved disc enlargement 41 in the groove of which is mounted a rubber stamping ring 42 on which are carried two diametrically oppositely disposed ink-stamping or marking dies 43. See Fig. 5. The sleeve includes a collar portion 44 and is split as at 45 and provided with a clamping screw 46 which enables adjustment of the sleeve about the axis of the shaft for the timing of the contacts of the dies 43 with the bottoms of the cans 16 being moved by the turret.

15 Each bearing portion 34 and 35 includes a slotted guide extension 47, and in the slot of each guide extension is mounted a bearing block 48. The blocks 48 rotatably support a shaft 49 which carries an applicator roll 50. The roll 50 is preferably formed of brass and it will be observed by reference to Fig. 1 of the drawings that this roll is positioned for contacting the ink-stamping ring 42. Each block 47 is engaged by an adjusting screw 51, as shown in Fig. 2, and by manipulation of these screws the pressure contact between the roll 50 and the ring 42 can be varied to determine the blackness of the inking.

20 35 A pinion 52 is secured upon the shaft 49 and is driven by a similar pinion 53 secured upon the driver shaft 31.

25 An ink fountain or reservoir 54, in the form of a sight feed liquid feeder, is secured as at 55 on the bearing extensions 47 and includes a drip nozzle 56 from which ink is deposited, drop by drop, onto the rotating roll 50. In order to properly spread and distribute the ink applied to the roll 50, I provide a wiper 57 which is supported as at 58 upon the frame 7 and contacts the periphery of the roll.

30 35 In operation the cans fed downwardly into the machine as shown in Figure 1 of the drawings are continuously moved, in a part circular path, past the ink-stamping station at which the ink-stamping devices are located. As the exposed can ends pass the marking station they are engaged, in rolling contact, by the dies 43 carried

by the ring 42. The parts are so timed that the ring 42 will rotate once for each passage of two cans so that the dies, disposed diametrically oppositely on the ring will engage alternate can ends. By adjusting the abutment plate 32 the machine can be made to accommodate cans of different heights, and by adjusting the sleeve 40 about the axis of the shaft 37 a proper timing of the die and can bottom contacts can suitably be gauged.

10 After being ink-stamped in the manner illustrated in Fig. 5 of the drawings, the continuously moving cans are fed onto the trackways 27 and out of the machine.

15 It is of course to be understood that the details of structure and arrangement of parts may be variously changed and modified without departing from the spirit and scope of my invention.

20 What I claim is:

1. In a can marking machine, a rotatable turret having a plurality of can receiving pockets for continuously moving cans with an end of each can exposed, an ink-stamping rotor continuously rotatable in a plane at right angles to the plane of rotation of the turret and having thereon a plurality of marking dies individually engageable in rolling contact with the exposed can ends, and means for retaining the cans against longitudinal displacement from the turret comprising a fixed guide rail disposed at the side of the turret adjacent the rotor and a guide member adjustable in the direction of the axis of the turret and disposed at the side of the turret remote from said rotor.

2. In a can marking machine, a rotatable turret having a plurality of can receiving pockets for continuously moving cans with an end of each can exposed, an ink-stamping rotor continuously rotatable in a plane at right angles to the plane of rotation of the turret and having thereon a plurality of marking dies individually engageable in rolling contact with the exposed can ends, and means for retaining the cans against longitudinal displacement from the turret comprising a guide rail disposed at the side of the turret adjacent the rotor and an end abutment disk threadably adjustable along the axis of the turret and adapting the turret to the moving of cans of different heights without necessitating any movement of adjustment of the rotor.

GEORGE F. JACKSON.
